MULTIPLEX CABLE CODE TELEGRAPHY
WITH DIVERSITY RECEPTIONHarold H. Beverage, Riverhead, N. Y., assignor to
Radio Corporation of America, a corporation
of Delaware

Application May 19, 1933, Serial No. 671,808

10 Claims. (Cl. 250—9)

This invention relates to signalling and in particular to multiplex cable code telegraphy with diversity reception. The cable code, commonly used on transocean cables, requires three conditions for transmitting intelligence. For example, on the cable, a positive direct current impulse of unit length may correspond to a dot in the Morse code, no current represents a space, and a negative direct current impulse of unit length corresponds to a dash in the Morse code.

In the Morse code, the letter "A" is a dot and dash, which would be transmitted in cable code as a positive current impulse, space or no current, and a negative current impulse, all units being of equal length.

In general in radio transmission of telegraphy messages over long distances, there are only two conditions, namely, "on" and "off" for single frequency transmission. That is, markings are represented by a pulse of high frequency for a dot, a pulse of different duration, perhaps longer, for a dash, and no signal for intervals and spaces.

I propose to obtain these three conditions by radiating three frequencies or two frequencies for marking and "off" or no energy for spaces. One feature of the present invention concerns means for receiving these two or more frequencies at high efficiency by what is known as diversity reception methods.

Most multiplex radio telegraph systems proposed in the past have been based on modulation methods. These methods result in low transmitter efficiency and very low power per channel, making the signals relatively unreliable due to fading, static, and other noises. Other methods use time division on a single frequency or single channel. These methods are efficient but are readily mutilated by extraneous noises such as static. They also require synchronous commutators at both ends of the circuit.

The multiplexing methods I am proposing allow the transmitter to be used at high efficiency, and provide a method of signalling which has greater freedom from extraneous noises than prior methods. In some embodiments of my invention, I also eliminate the necessity of using a synchronous commutator at the receiving end.

In my United States application Serial No. 661,947, filed March 21, 1933, now United States Patent #2,025,190 issued December 24, 1935, I described a method for multiplex cable code signalling using five frequencies, or four frequency and "off", for two channels, and seven frequencies, or six frequencies and "off", for three channels. In this system a commutator is used at

the transmitter for separating the channels while selective filters are used at the receiver for separating the channels, thus doing away with the necessity of using a synchronous commutator at the receiver.

My present invention also contemplates a method using cable code on two channels with two or three frequencies in which synchronized commutators for time separation are used at each end with diversity reception at the receiver.

My present invention involves a method of and means for applying diversity reception to (A) single channel cable code using two or three frequencies; (B) two channel cable code with commutator at the transmitter and frequency selection at the receiver, using four or five frequencies; (C) two channel cable code with synchronous commutators at both transmitter and receiver, using two or three frequencies.

In describing my invention reference will be made to the attached drawings, in which:

Figure 1 shows a diversity receiver of code signals transmitted on a single channel by a system similar to the system disclosed in United States application Serial No. 661,947, filed March 21, 1933, now United States Patent #2,025,190 issued December 24, 1935;

Figure 2 is a curve explaining the operation of the receiver of Figure 1;

Figure 3 is a circuit diagram of a transmitting system by means of which cable code on two channels utilizing 4 or 5 frequencies may be sent out;

Figure 4 is a receiver of the diversity type for receiving signals as sent out from the arrangement of Figure 3;

Figure 5 is a curve explaining the operation of the filters of Figure 4;

Figure 6 illustrates a modified transmitter and receiver; while,

Figure 6a illustrates a modification of a feature of the circuit of Figure 6.

The manner in which I apply diversity reception to a single channel cable code signalling system using two or three frequencies will now be described.

In Figure 1, I have shown a method for applying diversity reception to cable code signals on a single channel. When no dots or dashes are being sent out on the channel the transmitter may radiate continuously at a frequency f_3 , or it may not radiate at all, as preferred. If a frequency f_3 is radiated by the transmitter, it is suppressed at the receiver and produces no effect on the recorder circuits. Hence the frequency f_3 or total

absence of signal, i. e., "off", corresponds to a "space" in the cable code. To transmit a "dot" in cable code the transmitter frequency may be changed to another frequency, assumed for purposes of description to be f_1 , which frequency may be higher than the frequency f_3 . This frequency f_1 may be passed through high pass filters at the receiver and may be utilized to raise the pen arm on the recorder, causing it to make a "dot". To produce a "dash" on the cable code, the transmitter frequency may be caused to shift to a frequency f_2 , which may be a lower frequency than frequency f_3 . Frequency f_2 may be passed through low pass filters at the receiver and utilized to cause the pen arm on the recorder to be pulled down below the zero line, making a mark corresponding to a "dash" in the cable code. Any transmitter which sends out signals as indicated above may be used. Preferably, a transmitter of the type disclosed in my United States application Serial No. 661,947, filed March 21, 1933, now United States Patent #2,025,190, issued December 24, 1935, is used to signal on a single channel.

The characteristics of the high pass and low pass filters for separating frequencies f_1 and f_2 and suppressing f_3 are indicated in Figure 2.

Returning to Figure 1, I have shown a receiving system of the diversity type consisting of three complete receivers, associated with antennae 1, which are spaced a distance apart on the order of 1000 feet. The signals are amplified at radio frequency by amplifier 3. The amplified signals are fed to a demodulator of the heterodyne type including a detector and oscillator 5. The demodulated signals are fed to an audio amplifier 7. The amplitude of the signals in the output of the audio amplifier 7 is controlled by potentiometer 9, which feeds into high pass filter 11 and low pass filter 13 in parallel. Inductance 19 and capacity 21 are connected in series across the filters and are tuned to suppress the spacing frequency f_3 . The characteristic of the filters are indicated in Figure 2. Each filter passes only a predetermined band of frequencies. Neither filter passes f_3 .

The filters 11 and 13 are followed by rectifiers 15 and 17 respectively. Additional amplifier stages may be used between the filters and rectifiers, if desired.

The output terminals of the rectifiers 15 associated with the high pass filters in all receivers are connected together and completed through a resistance 23 as shown. The IR drop through this resistance 23 cooperates to operate the keyer unit, consisting of vacuum tubes 25, 37 and 39, and associated equipment.

The output terminals of the rectifiers 17 are connected together and completed through a resistance 23' as shown. The IR drop through resistance 23' cooperates to operate as the keyer unit including the tubes 25', 37', 39' and associated circuits as shown. The keying unit connected with filters 15 operates as follows:

When no signal is being received no signals are passed through the high pass filters 15. Under these circumstances tube 25 is biased to be conductive and is passing plate current from battery 27 through resistance 29. Battery 31 is adjusted to such a value that the voltage of battery 31 added to the IR drop across resistance 29 is sufficient to bias the grids of tubes 37 and 39 to such a negative potential as to make the tubes non-conductive and completely cut off the plate current in push-pull tubes 37 and 39. Consequently, the audio tone from oscillator 35 tuned to the frequency of filter 45 is unable to pass through the

push-pull tubes and through the high pass line filter 45 to the line 51.

Now, if frequency f_1 is emitted by the transmitter, current passes through the high pass filters 11 to the rectifiers 15, and the rectified currents from all receivers pass through resistance 23. If the sum of these rectified currents is large enough to produce an IR drop across resistance 23 of sufficient intensity to negatively bias the grid of vacuum tube 25 to a point at which cut off takes place, no plate current flows in 25 and no current passes through resistance 29. The grids of the pushpull tubes 37 and 39 are now biased by the amount of battery 31 alone, since there is no IR drop in resistance 29.

The bias on the grids of 37 and 39 due to battery 31 alone is such that the pushpull tubes 37 and 39 will amplify the oscillations impressed on the input circuit of said tubes from oscillator 35. This amplified current passes through transformer 43 and high pass line filter 45 adjusted to pass oscillations of the frequency of the oscillator 35 to the line 51. Thus during the time a signal of frequency f_1 is emitted and received a tone of a frequency determined by the oscillator 35 is sent over the line 51.

At the central office, this tone is received from the line 51 through transformer 53, passes through high pass filter 55, and is amplified in amplifier 57. The grid electrodes of rectifier tubes 61 and 79 are normally biased to a negative value by the battery connected thereto so as to cut off or render said tubes nonconductive. Amplified tone from amplifier 57 applied to the grid electrode of tube 61 overcomes the normal negative bias thereon to make the tube conductive. This causes plate current to flow through winding 63 of the polar relay, pulling up the tongue 65 to close a circuit including source 69, lead 71, ground, winding 85, contact 65 and lead 67. Positive current passes through the coil 85 of recorder 93. This positive current causes the pen 89 to rise, making a mark on the moving tape or recording medium 91, as long as frequency f_1 is emitted by the transmitter and received by any of the several receivers.

If the frequency sent out by the transmitter under keying action now shifts to f_3 this frequency is suppressed by the inductance-capacity circuit 19-21 at the receivers and no tone is received over the line. Tube 25 is conductive, current passes through resistance 29, tubes 37 and 39 are non-conductive, and no current goes over line 51. Consequently, the current in both tubes 61 and 79 falls to zero, equal or no currents flow in windings 63 and 81, and the tongue 65 of the polar relay takes up a central position and no current flows through the recorder coil. The recorder pen makes the "spacing" or no signal line.

Now if the transmitter is keyed to send out frequency f_2 , current passes through low pass filter 13 and rectifier 17 of all receivers, and operates the second keying unit. Tube 25', normally conductive, is biased to "cut off" by current flowing in resistance 23'. The absence of current in 23' causes the potential on the grids of tubes 37' and 39' to become more positive so that these tubes are now conductive. The tone from oscillator 47 is passed through low pass filter 49, adjusted to pass the frequency of the oscillator 47, and over the line 51, through low pass filter 73, and causes tube 79 to become conductive and to pass current through relay winding 81. This pulls tongue 65 down and completes a circuit through battery 69.

and winding 85 so that negative current passes through 85, causing the recorder pen 89 to be pulled down below the spacing line during the time frequency f_2 is emitted and received. The 5 operation just described has formed the letter "A" in cable code on the recorder slip, as shown. The three letters indicated on the recorder slip in Figure 1 are "A", "B" and "C".

From the description of the operation of #1 10 keyer unit, it will be seen that the intensity of the line tone from oscillator 35 is independent of fading as long as the sum of the rectified currents from the three receivers is sufficient to bias tube 25 to cut off. If the sum of the rectified currents 15 exceeds this value, nothing happens, since tube 25 can not produce any further effect after its plate current is reduced to zero. Consequently, if the input to resistance 23 is adjusted to cut off tube 25 with the minimum of the sum of the 20 three rectified currents, steady signals will be obtained on the line.

It has been found by experience that short wave 25 signals received on antennae spaced some distance apart fade independently. Hence the rectified current from one receiver may be strong when the current from another receiver fades out and vice versa. Consequently, the use of several 30 receivers greatly reduces the chances of all of the rectified currents dropping to such a low 35 value that they will not initiate operation of the keying units.

Three receivers are normally used in practice, and the extension of the system to use more receivers will be obvious to one skilled in the art.

35 Some added advantages of the system just described will now be enumerated.

Since in this system "dot" and "dash" signals occur at two different frequencies, we have frequency diversity in addition to space diversity.

40 We might get a partial fade on one frequency, but no fading on the second frequency, in which case, for example, the recorder might show a mutilated "dot" but a perfect "dash", which would readily identify the letter.

45 In this system all characters, i. e., dots, spaces, and dashes, are of equal length so that the absence of a character due to fading or other cause is immediately noticeable.

50 In this system there is no possibility of mistaking a "dot" for a "dash" or vice versa.

Furthermore, if static is present, it would have a tendency to come through both the high pass and the low pass filters more or less equally, thus tending to excite both windings of the relay 55 and causing it to remain in its neutral position.

Therefore, there would be fewer static crashes registered on the recorder tape, particularly during spacing intervals.

In my United States application Serial No. 60 661,947, filed March 21, 1933, now United States Patent #2,025,190, issued December 24, 1935, I disclosed a method of using a synchronous commutator at the transmitting station with arrangements for transmitting four or five frequencies 65 for multiplex cable code signalling on two channels. In this system no commutator is necessary at the receiver because the signals on the several channels are separated by using suitable filters for the four or five frequencies.

70 In Figure 3 I have shown a new means for and a method of transmitting these frequencies. The system and method shown is a modification of the method and system disclosed and claimed in my aforementioned application.

75 In Figure 3, 115 is a commutator with odd alter-

nate segments connected together and to slip ring 109 contacting with brush 105. The remaining even numbered segments are connected with slip ring 111 and brush 107. To brush 105 is connected the tongue 119 of relay 110 associated with 5 automatic sending head 102 for channel #1, while brush 107 is likewise connected to the tongue 103 of relay 104 associated with automatic sending head 104 for channel #2. The sending heads have sprockets which pull the perforated tapes 10 106 and 108 respectively over the keying heads. On channel #1, for example, contacts 112 and 114 make contact with 113 if there are holes in the paper tape or other perforated medium. If there are no holes in the perforated medium, no 15 contact takes place. Therefore, this device sends positive and negative impulses from battery 116 to relay 110 in accordance with the code letters punched on the tape or perforated medium. These automatic keying devices may be the same 20 as the automatic devices used in my United States Patent #2,025,190 issued December 24, 1935, or any type such as the Wheatstone, Creed, or Morkrum-Kleinschmidt.

The relay contact 119 makes contact through 25 resistance R_1 or R_4 according to whether the winding 110 is connected in series with 114 or 112 and receives a positive or negative current impulse from battery 116. The circuit may be traced from R_1 through brush 105, slip ring 109, 30 a #1 segment of the commutator to brush 120, battery 121, winding 123 to ground, thus completing the circuit. The current through winding 123 of transformer 129 changes the saturation 35 of the iron, and this changes the inductance of winding 131, which is in series with oscillator circuit 133-135. Hence the frequency generated by tube 139 is changed to some definite value f_1 , which may be further amplified by power amplifier 143 and radiated on antenna 145. 40

In like manner when one of the contacts in the keying head 104 is closed a positive or negative current impulse passes through 101 to close the armature 103 on one contact. If at the same instant the brush 120 rests on one of the #2 segments current determined in part by either R_2 or R_3 passes through 123 and a different frequency f_2 or f_3 is developed in 139 and radiated. 45

The resistances R_1 , R_2 , R_3 and R_4 are individually adjusted for such current values as may be 50 required to produce the necessary degree of saturation in the transformer 129 to cause the oscillator 133 to oscillate at the desired frequencies f_1 , f_2 , f_3 and f_4 . If both channels are spacing, there is no current in the saturation winding 123, 55 and the transmitter radiates at its lowest frequency f_5 .

In Figure 3, the resistances R_1 , R_2 , R_3 and R_4 are numbered according to the frequencies emitted. Channel #1 would correspond to f_1 for 60 dot, f_4 for dash, and f_5 for space. Channel #2 uses f_2 for dot, f_3 for dash and f_5 for space.

The commutator 115 and transmitter heads 102 and 104 must be driven at the same speed, preferably from the same drive shaft as shown, which 65 keeps the commutator 115 and transmitter contacts in 102 and 104 operating in perfect phase relation. This is necessary because channel #2 must mark during the spacing intervals on channel #1 and vice versa, and it is obvious that the 70 relay tongues 119 and 103 must operate during the intervals when the brush 120 is on a segment corresponding to the channel which is marking.

The letters "A", "B", "C" in cable code are shown on Figure 3 for channel #1 and X, Y, Z 75

are shown for channel #2, with their corresponding transmitter frequencies. Below these curves is shown the composite resulting frequencies radiated by the transmitter. The spacing frequency f_5 occurs only when both channels are spacing, and, obviously, f_5 might be omitted entirely if arrangements were made whereby zero current through the saturation transformer allowed a relay to open, causing the transmitter to cease 10 radiating. However, it is somewhat easier to allow the transmitter to continue to radiate at some frequency f_5 . Obviously, if desired, f_5 may be made adjustable by passing the proper amount of current from battery 121 through the saturation winding 123. This could be accomplished by placing a suitable resistance between the brush 120 and ground.

The arrangements for receiving the transmissions from the transmitter of Figure 3 will be 20 readily understood, as it is an extension of the system already described for single channel operation.

One suitable arrangement is indicated in Figure 4. Here three receivers are shown, each receiver 25 being equipped with five band pass filters, adjusted to correspond with the spacing of the transmitter frequencies f_1, f_2, f_3, f_4 and f_5 . The filter characteristics are indicated in Figure 5.

Assume that the transmitter of Figure 3 has 30 been put in operation and the automatic keying heads 102 and 104 are running and start to send out the letter A. A frequency f_1 is radiated first.

The output of #1 filter on each receiver is associated with an amplifier-rectifier and all #1 35 rectifiers are connected in parallel across the input resistance of #1 keying unit, from which #1 tone passes to the line L. At the central office, #1 tone passes through #1 filter, #1 amplifier, #1 rectifier and causes the pen of #1 recorder to 40 rise, marking a dot on the recorder slip. During the next interval, the transmitter radiates f_3 , so #1 recorder drops back to spacing. If f_3 is traced through the receiver of Figure 4, it will be noted that #2 recorder pen is pulled down making a 45 dash on the slip.

In like manner, the other frequencies sent out by the transmitter of Figure 3 may be traced through Figure 4 to show how the characters are formed, as the receiver of Figure 4 is assumed to 50 be responding to the signals sent out by the transmitter of Figure 3.

In Figure 4, telephones are shown connected across filter #5. This is for the purpose of lining up the received frequencies with the corresponding filters. For example, the frequencies might be radiated differing by a fixed amount, such as 170 cycles. At the receiver the oscillators in the detectors may be set so that the spacing frequency f_5 is, say, 595 cycles. Then $f_4=765$ cycles, 55 $f_3=935$ cycles, $f_2=1105$ cycles, and $f_1=1275$ cycles.

Alternatively, f_5 may be adjusted for "zero beat" and the other frequencies adjusted to fall in their respective filters. Furthermore, arrangements could be made whereby f_5 may be used to hold the receiver oscillators automatically at the right frequency. This may be accomplished by utilizing frequency f_5 to actuate mechanism to automatically tune the oscillators 70 at the receiver to a frequency which when combined with the received frequency results in a constant frequency beat note. Such a correcting device has been described in United States application Serial No. 692,092, filed October 4, 1933, 75 and in United States application Serial No.

675,536, filed June 13, 1933. This arrangement would automatically keep the frequencies lined up in their corresponding filters.

The system disclosed in Figures 3 and 4 also has the advantages of frequency diversity, static 5 balancing in spaces, etc., as enumerated in connection with the single channel system of Figure 1.

Some advantages may be gained in some cases both at the receiver and at the transmitter if a 10 commutator is used to separate the signal elements at the receiver as well as at the transmitter. In this case both commutators must operate in synchronism. When using codes, like the Baudot code, where all letters have the same 15 number of unit elements, it is feasible to send synchronizing impulses for periodically correcting the speed of the receiving commutator. In the case of the cable code, however, the letters contain variable numbers of elements, and it is 20 more difficult to fit in the synchronizing correction impulses. Therefore, it is preferable to use independently driven commutators at the transmitter and at the receiver operated from an extremely accurate source of frequency. It is relatively simple to independently drive the two commutators at speeds differing as little as 1,000,000 25 to 1, in which case occasional manual correction of the phase relations between the commutators at the transmitter and receiver should produce 30 satisfactory results.

Where synchronous commutators are used, three frequencies instead of five frequencies may be used for two channel multiplex code signalling. In this case the receiver of Figure 1 may be used 35 instead of the more complicated receiver of Figure 4.

An arrangement for two channel cable code signalling with independent synchronous commutators at the receiver and the transmitter is shown 40 in Figure 6. Here 149 and 186 are the transmitting and receiving commutators respectively which revolve in synchronism. The automatic senders shown schematically at 152 and 154 are driven from the same source as the transmitting 45 commutator 149, and said drive is coordinated with the drive of 149 so that the relay tongue 156 is always marking when relay tongue 157 is spacing, and vice versa. The relays are connected through brushes 160 and 161 to slip rings connected to alternate commutator segments, as shown. Brush 163 bearing on the commutator 149 is always in contact with one of the #1 segments when the tongue 156 of #1 relay is marking, and passes either positive or negative current 55 to the winding of relay 164 according to whether the letter character being transmitted throws the tongue 156 to battery 165 or 166. The tongue 167 of polar relay 164 applies a different potential to the grid of tube 168 according to which of the 60 contacts connected with source 169 is closed by the tongue 167, thus varying the impedance or conductance of the tube 168 and thereby varying the effective capacity of condenser 170. Condenser 170 and tube 168 in series are, in effect, connected 65 across an oscillating circuit connected as shown between the anode and cathode of tube 171. Varying the capacity of the condenser 170 varies the electrical characteristics of the oscillation circuit connected with 171 and thereby varies the 70 tune of the said circuit. This circuit determines the frequency of the oscillation generated by 171. Therefore, the frequency generated by tube 171 is dependent on the position of the tongue 167 of relay 164, and may generate any one of three fre- 75

quencies according to whether relay tongue 167 is closed "down", closed "up", or is "open", or in a neutral position. The three frequencies may be designated as f_1 for "dot", f_2 for "dash" and f_3 for "space", to correspond with the receiver of Figure 1.

The oscillations developed by the oscillator 171 are amplified by power amplifier 175 and radiated by antenna 176.

10 It is obvious that battery 169 may be adjusted to give any desired spacing between the frequencies f_1 , f_2 and f_3 . The positive and negative arrangement shown, however, produces f_1 higher, and f_2 lower, than f_3 to correspond with Figure 1.

15 The arrangement shown here, including the tubes 168 and 170 and associated circuits including the capacity 170, all of which are used for shifting the frequency generated by the tube 178 and its circuits, are similar to some extent to the 20 arrangement disclosed in United States application Serial No. 563,725, filed September 19, 1931, now Patent #2,033,231 issued March 10, 1936.

25 The receiver 180 of Figure 6 is identical with one of the complete receivers of Figure 1, and the relay tongue 183 of Figure 6 corresponds to relay tongue 65 of Figure 1. For simplicity I have shown a single receiver connected to relay 182, although it will be obvious that as in Figures 1 and 4 several receivers similar to 180 may be connected 30 with the relay 182 for diversity purposes. Instead of operating a single recorder directly, however, tongue 183 of Figure 6 is connected to a brush 184 bearing on the segments of synchronous commutator 186, thence through brushes 187 and 189 to recorders 190 and 191 respectively.

35 The operation of the system is obvious. For example, supposing the transmitter is producing or making a "dot" on channel #1, relay tongue 153 will swing over to positive battery 165, and brush 40 163 will be in contact with a #1 segment on commutator 149. Positive current in the winding of relay 164 will throw tongue 167 down, putting negative bias on the grid of tube 168. This decreases the effective capacity of condenser 170, thereby 45 causing frequency f_1 to be produced and radiated. At the receiver 180, f_1 will pass through the high pass filters (not shown here but shown in detail in Figure 1) and throw relay tongue 183 up to complete a circuit through the positive battery 50 179. Brush 184 will be in contact with a #1 segment on commutator 186 and will complete a circuit for positive current through brush 187 to recorder #1 causing the pen to rise and make a dot corresponding to that originally sent. Recorder #2 will be spacing because no current is reaching any of the #2 segments from brush 184.

55 The manner in which the dashes and intervals are sent out from the transmitter of Figure 6, picked up by the receiver, and made to produce desired markings on the recording medium should be obvious from the above description and a statement of said operation is thought unnecessary and superfluous at this point.

While I have shown the transmitters and receivers as including thermionic tubes of the triode type, it will be understood that by such showing I do not intend to limit the invention to the use of triodes since, obviously, any tubes of the appropriate characteristics in use today may be included in said circuits with or in place of the triodes. For example, screen grid tubes, pentodes, etc., are extremely well adapted to utilization in the circuits.

In the arrangement illustrated in the several 75 figures in the drawings magnetic means and va-

riable capacitive means including a capacity controlled through a thermionic tube have been utilized to produce the frequency shift of the oscillations sent out at the transmitter. It will be understood that any other method and means for producing frequency shift or phase modulation may be used. For example, I may use a piezo-electrical controlled oscillator, the frequency of the crystal of which may be shifted by mechanical means which varies at the keying frequency, the air gap of the crystal. Furthermore, the frequency of the crystal controlled oscillator may be shifted or varied by connecting the variable capacitor illustrated in Figure 6 in parallel with a piezo-electric crystal. In this arrangement extremely constant frequency oscillations, the frequency of which may be shifted to produce the keying indications, may be obtained. The frequency may also be varied by connecting a vacuum tube in series with an inductance instead of a capacity, as shown in Figure 6a, or by shunting a vacuum tube across a capacity or inductance in series with another capacity or inductance. It is obvious to one skilled in the art that varying the control voltage on the grid of the vacuum tube causes it to act as a variable resistance, thereby varying the current flowing through the elements in series or in shunt with the vacuum tube, which, in turn, varies the constants of the associated vacuum tube oscillator and causes the frequency to vary by a predetermined amount depending on the value of the bias applied to the grid of the vacuum tube.

Having thus described my invention and the 35 operation thereof, what I claim is:

1. Means for receiving multiplex signals on several channels composed of impulses of different frequencies on each channel comprising, a plurality of signal receiving means located at 40 spaced points, each of said signal receiving means including signal demodulating means, a plurality of filters connected with each demodulating means of each receiver, there being a filter connected with each receiver for each frequency used, signal recording means, a plurality of thermionic oscillators, thermionic blocking means interposed between each of said oscillators and said recording means, and thermionic coupling means interposed between the filters of said receivers 50 and each of said blocking means.

2. Means for receiving multiplex signals comprising, high frequency oscillations, the frequency of which is shifted to produce signal markings on several channels including, a plurality of receivers located at spaced points, each receiver including a signal demodulating means, a plurality of filters connected with each receiver, there being a filter for each frequency on each channel, a plurality of keying units, each 60 of said keying units being connected with a filter in each of said receivers, there being a keying unit for each frequency used, each of said keying units including a continuously operative oscillation generator, a recording device, thermionic blocking means interposed between each of said oscillators and said recording device, and a thermionic coupling tube connecting each of said blocking means to similar filters in each of 65 said receivers.

3. Means for receiving multiplex signals comprising, high frequency oscillations, the frequency of which is shifted to produce impulses of high frequency oscillations, the frequencies of which are characteristic of signal markings on 75

several channels including, a plurality of receivers located at spaced points, each receiver including a signal demodulating means, a plurality of filters connected with each receiver, there being a filter for each frequency used on each channel, a plurality of tone keying units, each of said keying units being connected with a filter in each of said receivers, a continuously operative oscillation generator in each of said tone keyers, a recording device, thermionic amplifiers interposed between each of said oscillators and said recording device, a circuit for biasing said amplifiers to cut off, and a thermionic coupling tube connecting each of said amplifiers to similar filters in each of said receivers, said coupling tubes each having a circuit, a portion of which is common to the biasing circuit of the amplifier to which it is coupled.

4. In a system for receiving multiplex signals, on several channels, composed of impulses of different frequencies on each channel, a plurality of signal receiving means located at spaced points, each of said signal receiving means including signal demodulating means, filtering means connected with each demodulating means of each receiver, signal recording means, a plurality of sources of oscillations, blocking means interposed between each of said sources of oscillations and said recording means, and coupling means interposed between the filters of said receivers and each of said blocking means.

5. In a system for receiving multiplex signals comprising high frequency oscillations, the frequency of which is shifted to produce impulses of high frequency oscillations, the frequencies of which are characteristic of signal markings on several channels, a plurality of receivers located at spaced points, each receiver including a signal demodulating means, a plurality of filters connected with each receiver, there being a filter for each frequency used on each channel, a plurality of tone keying units, each of said keying units being connected with a filter in each of said receivers, a continuously operative oscillation generator in each of said tone keying units, a plurality of recording devices, blocking tubes interposed between each of said oscillation generators and said recording devices, a circuit for biasing each of said blocking tubes to cutoff, and a thermionic coupling tube connecting each of said blocking tubes to similar filters in each of said receivers, said coupling tubes each having a circuit a portion of which is common to the blocking tube to which it is coupled.

6. The method of multiplex signalling on several channels simultaneously by time separating the several signals on the several channels, and frequency separating the signal elements on each channel at the transmitter which includes the steps of, receiving signals on all of said channels at a plurality of spaced points, separating out like signal elements received at the several points, rectifying the same to produce rectified currents, combining the rectified currents, producing oscillations, and recording said oscillations as long as said combined rectified currents are above a predetermined value.

7. The method of receiving multiplex signals on several channels which signals are formed by simultaneously time separating the several signal elements on the several channels and frequency separating the signal elements on each channel, which includes the steps of, simultaneously receiving energy portions characteristic of all of the signal elements at spaced points, segregating

the signal elements transmitted on the several channels and separating the signal elements on each channel and producing energy characteristic of each signal element on each channel to reproduce the original signal when the energy received at one or more of said points exceeds a predetermined intensity.

8. A diversity system for receiving multiplexing signals produced by time separation of the signal elements on several channels and frequency separation of the signal elements on each channel comprising, a plurality of receivers, filter circuits connected with each receiver for separating signal elements of like frequency, there being a filter for each frequency used and several filters for each receiver, a rectifier connected with each filter, signalling recording means, normally inoperative energizing means connected with said recording means, there being an energizing means for each channel, and means connected with said rectifiers and said energizing means for rendering the same operative on the receipt of signals on any of said receivers or several of said receivers which produce currents of a predetermined intensity in the output of one or more of said rectifiers.

9. In a multiplex transmission system, a plurality of sources of direct current impulses, each source comprising impulses of different polarity which polarity is characteristic of signalling markings, an electron discharge tube having anode, cathode and control grid electrodes, oscillation generating circuits connected between said control grid and cathode and between said anode and cathode, a reactance connected with one of said circuits, a magnetic relay having a winding, a movable contact and a pair of fixed contacts, an additional electron discharge tube having an anode, a cathode, and a control grid, a connection between the anode and cathode of said additional tube and said reactance, a connection between the control grid of said additional tube and the movable contact of said magnetic relay, sources of potential of different polarity connected to said fixed contacts, circuits connecting the winding of said magnetic relay to said first named direct current impulse, sources and means in said last named circuits for closing and opening the same at signal frequency.

10. In a system for receiving multiplex signals comprising high frequency oscillations, the frequency of which is shifted to produce impulses of high frequency oscillations, the frequencies of which are characteristic of signal markings on several channels, a plurality of receivers located at spaced points, each receiver including a signal demodulating means, a plurality of signal filters connected with each receiver, there being a filter for each frequency used on each channel, a plurality of tone keying units, each of said keying units being connected with a signal filter in each of said receivers, an oscillation generator in each of said tone keying units, each of said generators producing oscillations of a different frequency, a plurality of recording devices, a blocking tube connecting each of said oscillation generators to at least one of said recording devices, a filter circuit for each of said generators in said last named connections, and an electron discharge tube connecting each of said blocking tubes to similar signal filters connected with said receivers, said coupling tubes each having a circuit a portion of which is common to the blocking tube to which it is coupled.
